F. H. HOWARD

HOIST CABLE SECURING DEVICE

Filed Jan. 14, 1925

Inventor
Frank H. Howard,

By

Attorney

UNITED STATES PATENT OFFICE.

FRANK H. HOWARD, OF READING, PENNSYLVANIA, ASSIGNOR TO READING CHAIN AND BLOCK CORPORATION, OF READING, PENNSYLVANIA, A CORPORATION OF PENNSYLVANIA.

HOIST-CABLE-SECURING DEVICE.

Application filed January 14, 1925. Serial No. 2,460.

To all whom it may concern:

Be it known that I, FRANK H. HOWARD, a citizen of the United States, residing at Reading, in the county of Berks and State of Pennsylvania, have invented certain new and useful Improvements in Hoist-Cable-Securing Devices, of which the following is a specification.

This invention relates to improvements in hoist cable securing means and the object is to provide a simple yet secure fastening for the end of a hoist cable at its point of engagement with the hook block.

In my present invention I have devised a very simple yet effective fastening or securing device, comprising two like members, to form the block, provided with an opening for the end of the cable, a depression for engaging the enlarged end of the cable, and a pin about which the cable is bent, whereby I secure a simple grip on the end of the cable from which it will not be possible to withdraw it by pulling on the cable.

The invention is more fully described in the following specification and clearly illustrated in the accompanying drawing in which:—

Figure 1, is a side elevational view of a hook block with my device in position, one of the block members being removed.

Figure 2 is a plan view of the device.

The numeral 1 designates the hook which has the usual collar 2 and bearing 3 in the block. The block in the present instance is made up of two like members 5, each substantially hemi-spherical in form and each formed in its meeting face with depressions 6 and 7, so that when both members are brought together these registering depressions will form centrally disposed openings for the cable 8. The block is provided with a pin or shaft 9 about which the cable turns and the two block members may be secured together in any suitable and convenient manner, as by screws 10.

The cable 8 is formed with an enlarged

end 12, and, in placing it in position in the block, the block members are parted, and the cable placed in the depressions 6—7 50 with the enlarged end 12 protruding from the surface of the block member, so that, when the block members are brought together, the cable end will be securely held therebetween, the head 12 bearing against the outer surface of the block, and the cable prevented from withdrawal from the block by pulling thereon.

With this securing device, there will be no tying or knotting of the cable end above 60 the block, as is usual, and the result is that I attain several inches additional travel, which in many instances is of very great value.

Having thus described my invention, I 65 claim and desire to secure by Letters Patent:—

1. In a hoist cable securing device, a pair of substantially hemi-spherical block members, a cable engaging pin carried by one member, depressions in the face of each member adapted to register with the depressions in the other member to form cable engaging space, a cable, provided with an enlarged extremity, lying within said space 70 while the enlargement rests against the outer surface of the block members, and means for securing the two block members together. 75

2. A cable end securing device comprising an enlargement on the end of the cable, a two part block having registering depressions in their meeting faces to accommodate the end of the cable while the enlarged extremity thereof rests against the outer face 80 of the block, a pin within the block about which the end of the cable is placed and means for securing the two parts of the block together to hold the cable end in position therein. 85

In testimony whereof I affix my signature.

FRANK H. HOWARD.
